Fig. 3.

The diagram illustrates a longitudinal section of a soil profile. It shows a thick, dark layer at the top labeled 20, which is partially eroded, indicated by a dashed line. Below this is a layer labeled 19. A horizontal arrow labeled 18 points to the right through a layer labeled 17. Layer 17 is bounded by a dashed line on the left and a solid line on the right. Layer 16 is a thin, light-colored layer at the bottom. Layer 15 is a thick, light-colored layer above layer 16. Layer 14 is a thin, dark layer at the very bottom. A vertical arrow labeled 12 points upwards through layer 15. A horizontal arrow labeled 13 points to the right through layer 15. A vertical arrow labeled 11 points downwards through layer 16. A horizontal arrow labeled 10 points to the right through layer 16. The labels 12, 13, 11, and 10 are positioned to the right of the corresponding arrows.

UNITED STATES PATENT OFFICE

2,498,297

DISPLAY APPARATUS

Francis Ralph Rambo and Michael Angelo, San Jose, Calif., assignors to Muirson Label Co., Inc., San Jose, Calif., a corporation of California

Application December 26, 1945, Serial No. 637,244

2 Claims. (Cl. 35—53)

1

This invention relates to devices for displaying labels for containers and the like, and particularly for displaying strip labels of the wrap-around type for cans and boxes.

It is an object of the invention to provide a device for displaying labels, before they are applied to a container, in such a manner that any part of the label may be observed substantially as it would appear when applied. This is a great advantage to a label salesman and to a prospective customer, who can quickly see what the label would look like on the goods. More specific objects and advantages of the invention will appear from the following specification and the accompanying drawing, in which:

Fig. 1 is a plan view of the device embodying the invention, showing a label associated therewith for display;

Fig. 2 is an end view of the device shown in Fig. 1, the thicknesses of the parts being exaggerated for greater clarity;

Fig. 3 is a side view of the device shown in Fig. 1, the thicknesses of the parts again being exaggerated for clarity; and

Fig. 4 is a side view similar to Fig. 3, but with a masking or cover sheet moved to display a different portion of the label than can be seen with the cover sheet in the flat position illustrated in Figs. 1 to 3.

Referring to the drawing, a base or support 10, that may be formed from cardboard, fiberboard, or any other rigid sheet material, provides an elongated, rectangular, label-receiving surface 11, preferably longer and wider than a label to be displayed. A transparent sheet 12, that may conveniently be made of cellophane or the like, is mounted on the label-receiving surface 11 in such a manner as to permit a sample label 15 to be slid between the support 10 and the transparent sheet. This may be accomplished by folding opposite edges 13 and 14 of the transparent sheet 12 back against the body of the sheet as shown in Fig. 2 and by securing the folded under edges to the label-receiving surface of the support with any suitable adhesive.

The transparent sheet 12 is preferably the same length as the label 15, and enough wider to permit the transparent sheet to be secured to the support 10 in the manner described while providing a pocket between the transparent sheet and the support of sufficient width easily to accommodate the label. A notch 16 may be provided in one end of the transparent sheet 12 to enable one employing the device to grasp the label with his fingers for withdrawing it from the pocket after it has been displayed.

2

A rectangular, opaque, flexible, masking sheet or cover sheet 19, preferably the same size as the support 10, is hingedly mounted at one end 20 to the support 10 adjacent the end of the transparent sheet 12 opposite the notch 16 therein. Any suitable means, such as an adhesive, may be employed for hingedly mounting the cover sheet on the support provided only that the material of the cover sheet is flexible enough to permit it to be bent sharply for swinging the body of the sheet into and out of superposed relation with respect to the transparent sheet 12 and the label 15 underlying it.

The cover sheet 19 is provided with a cut-out or window 21 adjacent the free end thereof, the window extending lengthwise of the cover sheet a distance equal to the diameter or width of a container (such as a tin can or a box) adapted to receive the label, and transversely of the cover sheet a distance approximating the width of the label 15. This window is bordered by a representation on the sheet 19 of the outlines of one panel of the container.

The device shown in the drawing is one particularly designed for displaying a label as it would appear when wrapped around a conventional tin can, and the window in the cover sheet 19 is bounded by parallel edges 22 and 23 and by oppositely curved elliptical edges 24 and 25 that define an opening having the same size and configuration as an isometric profile of the cylindrical wall of a can. The exposed surface of the cover sheet, when it is superposed over the label 15, has depicted thereon adjacent the elliptical edges 24 and 25, respectively, isometric representations of the top 26 and bottom 27 of a can. With a portion 28 of the label 15 visible through the window 21 and the transparent sheet 12, the top and bottom representations 26 and 27 are disposed so as to give the illusion of the label applied to a can. All the other parts of the label design beyond the window 21, shown in dotted lines in Fig. 1, are obscured by the opaque cover sheet. By flexing the cover sheet 19 in an upward direction adjacent its hingedly mounted end 20 and by sliding the window portion 21 thereof along the label from one end thereof to the other, as indicated in Fig. 4, any part of the label may be viewed substantially as it would appear with the label applied to a can.

In displaying a box label the isometric representation of a box will be printed or affixed to the cover sheet 19 with its main panel cut out to show the label through the opening.

Obviously, if desired, more than one portion of a label can be displayed at one time by pro-

viding a plurality of similar windows 21 in spaced-apart relation along the length of the cover sheet 19.

To employ the above described device for displaying a label, the cover sheet 19 is first swung away from the support 10 to uncover the transparent sheet 12. After inserting the label under the transparent sheet, the cover sheet is swung back into superposed relation with respect to the transparent sheet and the label. One view of the label is thereby presented, as illustrated in Fig. 1. Then, by flexing the cover sheet and moving the window portion thereof in the manner described above, all parts of the label may be viewed substantially as they would appear with the label applied to a can while rotating the can to expose all sides thereof.

As will be apparent from the foregoing, the described embodiment of the invention may readily be modified for displaying various types of labels and package wrappers as they would appear on any type of container. It will also be apparent that numerous structural modifications of the device may be made while employing the features constituting the gist of the invention. Therefore, it is intended that the following claims shall cover all such modifications as fall within the natural scope thereof.

We claim:

1. A device adapted to display while in the flat continuously selected portions of a whole label so as to permit viewing of the label as it would appear applied to a cylindrical container, comprising means for supporting a label in a substantially flat position, a flexible opaque member overlaying said means and said label, said member having one of its ends near and parallel to an end of said label secured to said supporting means and having its other end unsecured, said member also having a cut-out near its unsecured end, said cut-out being of a size about equal to the height and diameter of the container for which said label is intended, whereby in viewing said label through said cut-out, said flexible member may

be buckled as said cut-out is moved in contact with said label toward its secured end.

2. A device adapted to display while in the flat continuously selected portions of a whole label so as to permit viewing of the label as it would appear applied to a cylindrical container, comprising means for supporting a label in a substantially flat position, a flexible opaque member overlaying said means and said label, said member having one of its ends near and parallel to an end of said label secured to said supporting means and having its other end unsecured, said member also having a cut-out near its unsecured end, said cut-out being of a size about equal to the height and diameter of the container for which said label is intended and having a representation in perspective of the top and bottom of a container bordering said cut-out, whereby in viewing said label through said cut-out, said flexible member may be buckled as said cut-out is moved in contact with said label toward its secured end.
